US00D773651S

(12) **United States Design Patent** (10) Patent No.: **US D773,651 S**
Chen et al. (45) Date of Patent: ** Dec. 6, 2016

(54) **CANNULA INSERTION TOOL**

(71) Applicant: **Medical Instrument Development Laboratories, Inc.**, San Leandro, CA (US)

(72) Inventors: **David Chen**, Fremont, CA (US); **Steven Smith**, Alameda, CA (US)

(**) Term: **15 Years**

(21) Appl. No.: **29/546,033**

(22) Filed: **Nov. 18, 2015**

Related U.S. Application Data

(62) Division of application No. 29/468,744, filed on Oct. 2, 2013, now Pat. No. Des. 746,443.

CLAIM

We claim the ornamental design for a cannula insertion tool, as shown and described.

DESCRIPTION

FIG. 1 is a perspective view of a cannula insertion tool showing our new design;

FIG. 2 is a first side view thereof;

FIG. 3 is a second side view thereof;

FIG. 4 is a third side view thereof;

FIG. 5 is a fourth side view thereof;

FIG. 6 is a first end view thereof; and,

FIG. 7 is a second end view thereof.

(Continued)

Portions of the cannula insertion tool shown in broken lines form no part of the claimed design.

1 Claim, 4 Drawing Sheets
